UNITED STATES PATENT OFFICE.

HIRAM M. LEWIS, OF ASHLAND, KENTUCKY.

FLUSH TANK.

Application filed January 14, 1929. Serial No. 332,376.

This invention relates to a flush tank for toilets, the general object of the invention being to provide means whereby the supply valve is opened when the seat is depressed 5 and the flow of water into the tank will act to close the flush valve, the valve being hollow and of considerable length so that the water will pass therethrough into the bowl when the water reaches a certain level in the 10 tank, the valve returning to open position as soon as the flow of water ceases due to the lifting of the seat.

Another object of the invention is to form the upper end of the flush valve of bowl shape, 15 which acts as a float to make the valve open quickly when the flow of water is cut off and this bowl shape also facilitates the entrance of the water from the tank into the hollow valve.

20 This invention also consists in certain other features of construction and in the combination and arrangement of the several parts, to be hereinafter fully described, illustrated in the accompanying drawing and specifically 25 pointed out in the appended claim.

In describing the invention in detail, reference will be had to the accompanying drawing wherein like characters denote like or corresponding parts throughout the several 30 views, and in which:

Figure 1 is a front view, with parts in section, of the invention.

Figure 2 is a similar view, but showing the flush valve in closed position.

35 Figure 3 is a side view, with parts in section.

In these views, the numeral 1 indicates the tank which is supplied with water from the pipe 2 which is provided with a self-closing 40 valve 3, the free end of the arm 4 of this valve engaging the elongated slot in a link 5 which is attached to a bracket 6 on the seat 7 of the toilet. These parts are so arranged that when the seat is in lowered position, the valve will be closed, but when the seat is in raised position, the valve will be opened so that water can enter the tank.

A lever 8 is pivoted to a support 9 within the tank and has pivoted thereto at one end 50 a hollow valve member 10 which is formed with a bowl-shaped upper end 11, the lower end of the valve member engaging a seat 12 in the connection 13 which connects the tank with the bowl. A weighted member 14 is 55 pivoted to the other end of the lever and is

formed with a socket 15 which receives the upper end of the supply pipe 2, the weight of this member 14 being sufficient to hold the valve member in raised position.

From the foregoing it will be seen that 60 when the valve 3 is closed, the valve 10 will be opened so that water can escape from the tank into the bowl. When the seat is lowered, the valve 3 will be opened and the flow of water from the pipe 2 into the tank, acting 65 against the walls of the socket in member 14, will raise the said member 14, thus causing the lever 8 to lower the valve member 10 upon the seat 12 so that water cannot escape from the tank into the bowl. When the water in 70 the tank reaches a level higher than the valve member, it will flow into the bowl-shaped upper end and through the valve into the bowl. When the seat is lifted, the valve 3 will be closed and the member 14 will move 75 downwardly, thus raising the valve member to permit the water in the tank to flow into the bowl to flush the same. The bowl part 11 acts as a float so that the valve member will raise quickly when the flow of water into the 80 tank ceases and thus facilitate the flushing action of the water in the bowl.

It is thought from the foregoing description that the advantages and novel features of the invention will be readily apparent. 85

It is to be understood that changes may be made in the construction and in the combination and arrangement of the several parts, provided that such changes fall within the scope of the appended claim. 90

What I claim is:—

A device of the class described comprising a bowl, a tank connected therewith, a hollow valve member for controlling communication between the tank and bowl, a lever pivoted 95 in the tank and having one end connected with the valve member, a weighted member connected with the other end of the lever and having a socket in its lower end, a supply pipe extending into the tank with 100 its upper end extending into the socket, a valve in the pipe and means for opening the valve when the bowl seat is lowered whereby water flowing into the tank from the pipe will raise the weighted member and lower 105 the valve member upon its seat, the water passing through the valve member when the water reaches a certain level in the tank.

In testimony whereof I affix my signature.
HIRAM M. LEWIS.
